MEDICINAL TREATMENT DEVICE

George W. Hipsley, Philadelphia, Pa.

Application December 29, 1933, Serial No. 704,589

3 Claims. (Cl. 128—136)

This invention relates to medicinal treatment devices, and more particularly, to devices for treatment of the nose, throat, and lungs.

The principal object of this invention is to provide an improved, small, practical, and efficient device for treating ailments and diseases of the before-mentioned parts of the body, without the annoyance and distress attending such treatments by inhaling liquid sprays or hot steam, as is the case with many other devices. This device is designed for use in any part of the world without the need of modern conveniences, such as gas or electricity, for its successful operation; and it functions to generate a relatively dry medicinal vapor from a liquid medicament, by passing a stream of compressed air in a novel manner through said medicament which is heated indirectly by water which is at a high temperature. Means are provided to effectively apply said medicinal vapor to the affected parts.

A further object of this invention is to provide a device which permits the mixing of desired quantities of air with the medicinal vapor, and to provide a variable means of escape to the atmosphere after said vapor has passed over the parts being treated, thereby effecting a douche action.

The apparatus is also designed with a pressure limiting device which relieves the pressure by allowing escape into the atmosphere when a predetermined value of pressure has been exceeded. Such a condition may occur when an obstruction is encountered in the part of the body being treated, and this pressure limiting device eliminates the possible danger of damage to such parts from an excessive pressure. The released pressure causes an audible indication which apprises the user that an obstruction has been encountered, and the proper adjustments can be made to secure the desired douche action.

These and other objects and features, as well as the construction of a preferred form of the invention, will be clearly understood from the following detailed description and the accompanying drawings. In the drawings:

Figure 1 is an elevational view showing the main parts of the device in section;

Fig. 2 is a plan view of the device;

Fig. 3 is an enlarged fragmentary sectional view;

Fig. 4 is a face view of the nozzle;

Fig. 5 is a sectional view along line 5—5 of Fig. 4;

Figs. 6 and 7 are perspective views of the nozzle parts;

Fig. 8 is a perspective view of an alternative form of nozzle;

Fig. 9 is a sectional view of the same;

Fig. 10 is a sectional view taken along line 10—10 of Fig. 9;

Figs. 11 to 14 are perspective views of the nozzle parts;

Fig. 15 is a face view of the medicament agitating nozzle;

Fig. 16 is a sectional view of the same;

Fig. 17 is a perspective view of the same;

Fig. 18 is a perspective view of a stopper plug; and

Figs. 19 and 20 are perspective views of modified nozzle parts.

Referring to the drawings, and particularly to Figs. 1 to 3, the device comprises a relatively small container 1 which is adapted to contain heated water or some other suitable heating medium. To the end that the container may be substantially filled with heated water during use of the device and in order that the water may be brought to a desired level, there is formed on the inside surface of the container an annular ridge or projection 2 which indicates the proper filling level. The container is constructed so as to retain the heat within the same or, in other words, to prevent heat transfer to the outside atmosphere. As illustrated, the container comprises an outer shell 3 and an inner shell 4 between which there is interposed suitable heat insulating material 5. There are provided on the container feet 6 and a handle 7.

The container is preferably shaped as illustrated and it is formed with a circular opening 35 at the top thereof defined by a conical wall 8. A resilient conical washer 9, which may be formed of rubber or other suitable material, seats snugly within the opening. A vessel 10, which is preferably formed of glass and shaped as illustrated, 40 extends through the opening to a point near the bottom of the outer container and seats snugly at the upper part of the container. This vessel is adapted to contain liquid medicament, as will be discussed hereinafter. Both the washer 9 45 and the upper part of the vessel 10 are flanged, as illustrated, and the washer is provided with annular recesses which receive annular ridges or beads formed on the outer surface of the vessel. By this construction, the vessel 10 is secured 50 firmly to the outer container and is held in proper position with respect thereto. Also, a tight seal is provided between the vessel and the container so as to prevent the escape of water or steam from the container. The washer 9 frictionally 55

engages the wall 8 of the container opening in the manner of a stopper and it may be withdrawn when desired, as will be clearly obvious. The vessel 10 will, of course, displace some water 5 when it is inserted in container 1, so that the water level will be as illustrated, the water substantially filling the container.

The upper open end of vessel 10 is shaped as illustrated and is also provided with a conical 10 surface 11 which is adapted to snugly receive a stopper 12. The stopper is provided with a central and side openings, as illustrated more clearly in Fig. 3. The central opening is enlarged and threaded at its lower end to receive tube 13. The 15 upper portion of the central opening is also enlarged and threaded to receive a bushing 14. This bushing is formed to provide a valve seat against which the valve ball 15 may seat. A spring 16 is arranged below the ball to urge the 20 same against the valve seat, the spring being retained in position by cap 17 which is screwed into the lower end of the bushing. Thus there is provided a spring operated check valve which permits passage of air in one direction only 25 against the action of spring 16 and which prevents the liquid medicament from being sucked up from vessel 10.

The upper part of bushing 14 is shaped so as to constitute a socket and to receive snugly a 30 tapered nipple 18 carried at the end of a flexible tube or conduit 19. This tube, which may be formed of rubber, is connected to a compressible bulb 22 (see Fig. 1) having an air inlet 23 provided with a check valve 24. The purpose of bulb 35 22 is to force air under pressure through tube 19 and through the check valve of bushing 14 to tube 13.

For the successful operation of my invention, a positive check valve is necessary, and must be 40 placed somewhere between the pressure generating means 22 and the liquid agitating member shown at the bottom of tube 13 and described hereinafter, to prevent the liquid medicament from being sucked up into the pressure generating 45 means. The usual method is to install an ordinary ball check at the discharge end of the pressure generating means. This method is not entirely successful in my device, for with continued use small quantities of liquid pass by this 50 ball check. To overcome this difficulty, I designed the spring check valve 15, 16, and placed it as shown in Fig. 3, as an integral part of the apparatus, which would not be the case if it were placed at the discharge end of the pressure generating 55 means as is ordinarily done. My arrangement makes possible the use of standard replacement parts, since tube 19 and bulb 22, which need replacing from time to time, are of ordinary construction. If the spring check valve were placed 60 at the discharge end of the bulb, it would cause considerable difficulty in the replacement of the bulb, because such a valve is not common in devices of this kind. The use of the spring check valve and its particular position and integral 65 association with the device is, therefore, a very important feature of the invention.

One of the side openings of stopper 12 is provided with a bushing 25, the upper portion of 70 which is shaped so as to constitute a socket and is adapted to receive a tapered nipple 26 carried at the end of a flexible tube or conduit 27, which, in turn, is connected to a discharge nozzle 28. Tube 27 functions to convey the vaporous particles of the medicament, which are formed in a 75

manner described hereinafter, from vessel 10 to discharge nozzle 28.

The other side opening of stopper 12 is enlarged and threaded at the upper portion thereof so as to receive a pressure limiting device 29, or, alternately, the solid plug 30 shown in Fig. 18. Device 29 comprises a tubular body 31 and an adjustable screw cap 32. The lower part of the body 31 is formed as a valve seat against which a valve ball 33 is pressed by spring 34, the spring being held in position by the cap. Cap 32 has an aperture therein within which is mounted an audible signal device consisting of flexed apertured disks 35. These disks form a simple whistle device, such as is commonly found in toys and like articles. By virtue of the adjustability of cap 32, the valve may be adjusted to any desired pressure. When, however, the pressure within vessel 10 exceeds the value at which the valve is set, ball 33 will be raised from its seat and the pressure will be relieved. The air passing through disks 35 will cause an audible whistling sound, thereby apprising the user of the fact that excess pressure has built up in the device due to an obstruction in the part of the body being treated. When the solid plug 30 is used instead of device 29, there will, of course, be no release of pressure through stopper 12. The solid plug, however, may be used, if desired, particularly by physicians or other persons who would not be likely to subject the affected part of the body to injurious pressure, and the plug may also be used with a modified form of nozzle described hereinafter.

The lower end of vessel 10 is preferably shaped as illustrated and there is provided on the inner surface of the vessel an annular rib or projection 36 to indicate the proper level of liquid medicament contained in the vessel. It will be seen that the body of the liquid medicament which should be contained in vessel 10 during use is relatively shallow as compared with the body of heated water surrounding the vessel. As will be seen, vessel 10 is substantially submerged in the heated water and the vessel is substantially completely disposed within the outer container. The lower end of tube 13 is of bulbous conical shape. The conical portion may be formed as a separate part screwed onto the lower flared end of tube 13 as at 37. The inverted conical part is provided with a plurality of circularly arranged tangentially directed openings 39 (see Figs. 15 to 17), which are adapted to discharge the air in a plurality of circularly arranged tangentially directed streams, as indicated by the arrows in Fig. 15. To the end that a whirling action may be obtained, the conical wall is formed so as to provide the tangential apertures 39 and indentations 38 leading therefrom. A small opening 41 is provided at the apex of the conical part.

By virtue of this construction, the circularly arranged air streams which are set up in the liquid medicament cause a whirling agitation of the medicament and thus break the heated medicament up into fine moisture-free particles and at the same time expend the force of the air stream. The shape of the lower end of vessel 10 greatly enhances this action as it causes the concentration of the whirling agitation action in a relatively small volume of liquid. The small opening 41 tends to relieve excess air pressures within the bulbous air emitter, which pressures would otherwise tend to detrimentally affect the whirling agitational action. This agitational ac- 75

tion not only serves to break up the liquid medicament into fine vaporous particles but it also prevents the splashing of the medicament up against the stopper which would necessarily occur if the air were directed vertically or radially. Thus escape of liquid particles of the medicament through the discharge opening of the device is effectively prevented. The shape of the medicament-containing portion of vessel 10 also has the advantage that it minimizes the volume of the medicament which is used, thereby making an effective treatment as economical as possible. This is important when it is considered that medicaments are usually expensive. The nozzle 15 28 comprises two parts 42 and 43, as shown in Figs. 6 and 7. Part 42 is cup-shaped and has an extending central tubular portion 44 which is adapted to be inserted in the end of the flexible tube 27, as illustrated in Fig. 1. The flat circular bottom of part 42 is provided with diametrically opposite openings 45, as shown in Figs. 4 and 6. Part 42 is adapted to receive part 43, which adapts the device for treating the nose, or part 42 may have mounted thereon part 43a 25 (see Fig. 20) which adapts the device for treatment of the mouth:

Part 43 consists of a shell which is adapted to fit snugly over the cylindrical portion of part 42 and is provided with a transverse wall 46 having 30 apertures 47 therein which may be brought into register with apertures 45, as shown in Fig. 4. The shell-like part 43 may be rotated when mounted upon part 42 so as to bring the said apertures into register or to position them out 35 of register. Wall 46 has a central aperture 48 through which a central discharge tube 49, formed at the lower end of tube 44, extends. The conical portion 50 of part 43 forms an annular chamber 51 about the discharge tube 49. The degree of register of openings 45 and 47 controls 40 the effectiveness of the annular passage to admit air at the nozzle and to relieve pressure and permit escape of medicament to effect a douche action.

45 This may be more clearly understood from a consideration of the actual use of the nozzle. Initially, the annular passage 51 may be closed by proper positioning of part 43 with respect to part 42. When the outermost annular edge of 50 nozzle is inserted in the nostril for treatment, the annular passage is substantially closed to the outside air. As long as no obstruction or resistance is encountered by the projected vaporized medicament, the device may be thus used. When, however, an obstruction is encountered, pressure will be built up in the device and this will be evidenced by the action of 55 the pressure limiting device 29, as above described. At such time, the user may regulate part 43 to provide the desired degree of opening of the annular chamber 51 to relieve the pressure and allow the escape of vaporized medicament to thus effect a douche action. Manipulation of part 43 also permits mixing of 60 desired quantities of air with the projected medicament.

Part 43a, which is designed for mouth treatment, is similar in construction to part 43 but differs therefrom in that it has an extended tube 70 52, which may be placed in the mouth upon the tongue. The tube may be knurled at 53 to permit grasping the same between the teeth at that point. The operation of the device with part 43a is the same as just described.

75 In Figs. 8 to 14, there is disclosed a modified

form of nozzle 28a which is adapted to automatically relieve the pressure at the nozzle and to give an audible indication when the pressure is relieved, to apprise the user of the fact that an obstruction has been encountered. This nozzle comprises a shell 54 having spaced transverse walls 55 and 56 with apertures 57 and 58, respectively. The shell carries a central tube 59 which is adapted for insertion in the end of a flexible tube, such as tube 27, and which is internally threaded to receive a discharge tube 60 (see Fig. 14). A pressure plate 61 (see Fig. 13) is slidably mounted upon tube 60 and is urged outward by spring 62. The shell 54 is provided with diametrically opposite recesses 63 which slidably receive projections 64 formed on the pressure plate. In this manner, the plate is held against rotation. The pressure plate is shaped as clearly illustrated in Figs. 9 and 13.

Shell 54 is adapted to receive an outer shell 65 which fits snugly upon shell 54 but is adapted for rotation thereon. Shell 65 has a transverse wall 66 with apertures 67 therein that are adapted to be brought into various positions with respect to plate 61 to effect any desired degree 20 of opening into the annular passage 68 formed about the discharge tube 60 by the conical portion 69 of shell 65. The cylindrical wall of shell 54 is provided with tapered openings 70 which are adapted to co-act with openings 71 in the cylindrical portion of shell 65, as shown in Fig. 8. By rotating shell 65, openings 71 may be brought into any desired degree of register with the tapered openings 70 to effect communication 25 of the chamber 72 with the outside atmosphere. The device is constructed so that register of openings 70 and 71 is substantially coincident with uncovering of openings 67.

When this nozzle is used, it is unnecessary to use device 29 and the solid plug 30 may, therefore, be inserted in place thereof. Initially, shell 65 will be positioned so as to close the various openings and the annular passage 68 will, therefore, be substantially closed. If an obstruction is encountered, however, and the pressure within the nozzle builds up beyond a predetermined value, the pressure plate 61 will be forced backward against the action of spring 62 by the pressure exerted on the plate through openings 67. The pressure plate will, therefore, move away from wall 66, thus permitting the release of the pressure into chamber 72 and through the openings 58, 57. The air passing from chamber 72 through those openings will cause an audible whistling sound because of the spaced relation of the apertured walls 55, 56. This will apprise the user of the fact that an obstruction has been encountered, and shell 65 may then be rotated to effect the desired degree of communication of passage 68 with the outside atmosphere through openings 67, 70, and 71. This will reduce the pressure at which the device is operated and, at the same time, will effect a douche action, the vaporized medicament flowing out through the openings after it has been projected upon the affected part of the body.

Shell 65 is adapted for treatment of the nose, while shell 65a (see Fig. 19) is adapted for treatment of the mouth. This shell is similar to shell 65, differing therefrom only in the provision of the extended tube 73. It is adapted to be used in the same manner as shell 65.

The alternative form of nozzle illustrated in Figs. 8 to 14 may be attached to a separate flexi-

ble tube similar to tube 27 and carrying a nipple, like nipple 26, so that the nozzles may be changed by merely withdrawing one nipple from bushing 25 and inserting the other nipple therein. In order that the openings may be closed when nipples 18 and 26 are withdrawn, there are provided stoppers 74 and 75 attached by chains to bushings 25 and 14, respectively. This effectively seals vessel 10 during non-use of the device and prevents evaporation of the medicament or the entry of foreign particles, thereby making possible several treatments without replacing the medicament. In order that the nipples and stoppers may be positively identified for insertion in the proper bushings, bushing 25, nipple 26, and stopper 74 are provided with circular flanges, while bushing 14, nipple 18, and stopper 75 are provided with non-circular flanges, as shown in Figs. 1 and 2.

20. The method of operation of the device is as follows: The heat insulated container 1 is filled with boiling water up to the ridge 2. The inner vessel 10 is mounted in the open end of container 1 and filled with the necessary medicament up to the ridge 36; stopper 12 being in place, the plugs 74 and 75 are moved and the hose connections made to their proper bushings. We are now ready to proceed with the treatment.

30. The nozzle 28, or the nozzle 28a, is placed firmly in the opening of the nostril, and effectively stops up the opening of same, allowing the medicinal vapor to be forced into the nasal cavity under a low pressure. The intermittent pressing of bulb 22 forces air through the check valve 15, 35 16 when it is discharged with a circular motion by the agitating nozzle 13, into the medicament at the bottom of vessel 10, which action causes the heated medicament to vaporize, after which it is conducted to the nostril by tube 27 and nozzle 28, or nozzle 28a.

40. The adjustable pressure limiting device 29 is used in conjunction with nozzle 28, which device releases when a predetermined value of pressure is exceeded, and gives an audible indication 45 (such a condition may occur when an obstruction is encountered in the part of the body being treated). The nozzle is then adjusted to allow the medicinal vapor to escape into the atmosphere after it has passed over the affected part, thereby 50 effecting a douche action. By substituting part 43a for part 43, the medicinal vapors may be injected directly into the throat by the tube 52 which is placed in the mouth.

55. Operation of the nozzle 28a is substantially the same as described, the principal difference being that the pressure limiting device and the audible indicator are incorporated in the nozzle itself instead of in the stopper 12 as in the other 60 case. Blank plug 30 is used in conjunction with nozzle 28a instead of device 29.

65. From the illustration and above description, it will be seen that the invention provides a compact device which may be conveniently used by anyone. The device is so designed that the medicinal vapor is discharged at a temperature not greatly exceeding that of the body, thereby eliminating the danger of catching more cold after a treatment, which might happen if the vapor 70 were very hot. Although the preferred form of the invention has been illustrated it will be understood that various changes and modifications, particularly as to details, may be made without departing from the spirit and scope of 75 the invention.

I claim:

1. In a device for generating and injecting a medicament in a relatively dry vaporous form into parts of the human body such as the nose or throat; a vessel adapted to contain a relatively shallow body of liquid medicament; and means for conveying air to a point inside near the bottom of said vessel and below the surface of the medicament; said vessel and said air conveying means being formed so as to provide a relatively restricted passage therebetween below the surface of the medicament; said air-conveying means having a plurality of circularly arranged tangentially directed air discharge openings, which in conjunction with said passage cause a whirling 10 agitating action of the air on the liquid medicament. 15

2. In a device for generating and injecting a medicament in a relatively dry vaporous form into parts of the human body such as the nose or throat; a vessel adapted to contain a liquid medicament, said vessel having a vapor outlet opening and an air inlet opening; a discharge nozzle connected to said vapor outlet opening and adapted for direct insertion into the opening of the body being treated and designed to completely stop off said opening from the outside air; means for supplying air under pressure to the interior of said vessel through the air inlet opening therein; a pressure relief device in communication with the interior of the vessel and responsive to pressure conditions existing therein to relieve the pressure existing within said vessel when such pressure exceeds a predetermined value, due to a stoppage of flow of the generated vapors through the nozzle which occurs under certain conditions arising in the part of the body being treated; and means on the nozzle for preventing operation of the pressure relief device, said means, when operated, permitting the generated vapors to effect a douche action within that part of the body undergoing treatment. 30

3. A device for generating and injecting a medicament in a relatively dry vaporous form into parts of the human body such as the nose or throat, without the need of inhaling said medicament into the lungs, comprising a relatively small outer container, adapted to be substantially filled from an opening at the top, with a liquid, such as water, heated to a predetermined temperature by an external source of heat not directly associated with the device; an open end inner vessel adapted to contain a relatively shallow body of liquid medicament, said vessel extending through an opening at the top of the outer container almost to the bottom of said container, and being disposed substantially entirely within said container, whereby the shallow body of medicament and a substantial part of the inner vessel are maintained at a desirable temperature by the enveloping heated liquid throughout the duration of a treatment; means for attaching said vessel to said container, and for effecting a tight seal between the vessel and the container at the top thereof, said container being entirely free of any external associated heating means, and serving as the only physical support for said vessel; air conveying means extending into the liquid medicament; said vessel and said air conveying means being formed so as to provide a relatively restricted passage therebetween below the surface of the medicament; said air conveying means having a plurality of circularly arranged tangentially directed air discharge openings, which in conjunction with said 70 75 80 85 90 95 100 105 110 115 120 passage cause a whirling agitating action of the air upon the liquid medicament; means for forcing air under pressure through said air conveying means; means for conveying vaporous particles of the medicament from the inner vessel to the part of the body being treated; a vapor discharge nozzle connected to said vapor-conveying means and adapted for direct insertion into the opening of the body being treated and designed to completely stop off said opening from the outside air; an adjustable pressure relief and audible signal device in communication with the interior of the vessel and responsive to pressure

conditions existing therein to relieve the pressure and to give an audible indication when such pressure exceeds a predetermined value due to a stoppage of flow of the generated vapors through the nozzle which occurs under certain conditions arising in the part of the body being treated; and means on the nozzle for preventing operation of the pressure relief and audible signal device, said means, when operated, permitting the generated vapors to effect a douche action within that part of the body undergoing treatment. 5 10

GEORGE W. HIPSLEY.
